PACKAGE

Frank Jeffery Clancy, Seattle, Wash., assignor of thirty-five one-hundredths to Andrew Gumnard and two one-hundredths to Florence N. Ashton, both of Seattle, Wash.

Application June 6, 1932. Serial No. 615,691

6 Claims. (Cl. 206—41)

My invention relates to packages, and more particularly to a receptacle adapted to contain such goods as cigarettes or the like.

A particular object of the invention is to provide a package adapted to be formed from a single sheet of paper blank stock or the like, or from a pair of such sheets, the blank being suitably formed and folded to provide integral side and end portions of the package.

10 A further important object of the invention is to provide a package having a substantially convexly curved side for convenience in fitting the vest pocket or other pocket of the user.

A further object of the invention in a certain preferred form of embodiment is the provision of a package having a concave side and a convex side, the package being adapted to be carried in the pocket of the user with the convex side outermost, whereby the package very accurately fits the pocket and reduces objectionable puckering of the garment to a minimum.

Another object of the invention is to provide a package of the character indicated which may be expeditiously and inexpensively formed from paper blank stock or equivalent material after preforming the blank and folding certain portions thereof in the novel manner hereinafter described to provide from the blank a pair of integral side portions and an end portion.

30 Other and further objects and advantages of the invention will more fully appear from the detailed description hereinafter of the principles of the invention as applied in certain preferred forms of embodiment.

35 In the accompanying drawing which forms part of this application for Letters Patent and in which the same reference character designates the same part in the several views:

Figure 1 is a plan view of a type of blank embodying certain principles of the invention;

40 Fig. 2 is an end perspective view of a package formed from the blank shown in Fig. 1;

Fig. 3 is a cross sectional view of the completed package;

45 Fig. 4 is an internal end view of the package showing the folded end structure in the interior of the package; and

Fig. 5 is a view of a completed package carried in the pocket of a user, showing the manner in which the package fits the pocket without puckering the material of the garment.

The conventional type of cigarette package now in use is substantially rectangular in cross section, both of its sides being of equal width, and the package being of uniform thickness

throughout its entire width. The shape of such a package not only renders the same inconvenient and cumbersome to carry in a vest pocket of the user, but results also, when carried in such a pocket, in the imposition of relatively great compressive stress on cigarettes positioned in the corners of the package, so that certain of the cigarettes become injuriously flattened. The present invention contemplates a novel form of package having an outer convex side, and in one form of embodiment having an inner concave side. In the corners of the package the convex side intersects the plane of the other side in a curve of relatively great radius, providing space in each opposite corner for one cigarette, instead of the two or three cigarettes commonly carried in the comparable portions of the conventional cigarette package. My new package is thus accommodated to the contour of the pocket, and the material of the pocket in which the package is carried is not deformed. The contained cigarettes are thus protected against injurious stresses of the pocket material, and the appearance of the garment, generally a vest, is not impaired.

Referring to the drawing, Fig. 1 shows a form of blank from which a preferred embodiment of the invention is produced. The blank is substantially rectangular, and is divided by the dotted line 1 into a relatively narrow side 2 and a wider side 3. The wider side 3 is adapted to be folded over, substantially on the line 1, and its free margin 4 is adhesively united to the free margin of the side 2, whereby the two sides of the package are associated in cooperating relationship.

The end of the package is formed by forming the lower margins of the blank as indicated in Fig. 1. The margin of side 2 is slit at 5, in substantial alignment with the median line 95 of the side, to divide the margin of side 2 into portions 6 and 7. These portions preferably form the outer ply of the package end by being superimposed on the margin 8 of side 3 adhesively secured thereto.

The package formed from the blank of Fig. 1 is designed to have one convex side and one concave side. Side 3, wider than side 2, is convexly curved, and its marginal portion 8, equal in length with the width of side 3, is longer than the width of side 2. Since the free edge of the portion 8 is turned substantially right angularly from the side 3 to lie substantially along the plane of side 2, it is necessary to reduce the effective length of said free edge. This reduction is convenient

110

ly accomplished by providing darts or tucks, 9, 9, inwardly from the free edge of the portion 8. Each tuck 9 is substantially triangular in contour and is folded along a line which substantially bisects the portion, as shown in Fig. 4.

Similar triangular folded areas are formed in the corners of the portions 6, 7, as shown at 10, 10, and in the corners of portion 8, as shown at 11, 11. The several corner areas are folded 10 on themselves to provide corner tucks for the package, thus materially reducing the thickness of the package in its corners as compared with its body portion.

The portion 8, after being folded as indicated, 15 is turned inwardly from side 3, and portions 6 and 7 are turned inwardly from side 2, superimposed on portion 8, and adhesively secured thereto to complete the end structure of the receptacle. However, before adhesively uniting the 20 two plies of the end, slit 5 is slightly opened, to render substantially arcuate the line of fold common to side 2 and portions 6, 7, and dispose the side 2 in a condition of substantially concave curvature, as shown in Figs. 2 and 4. Setting of the adhesive fixes the preformed curvatures of the sides through the medium of the integral end portions of the package.

It is to be observed that as regards the specific embodiment of the invention hereinabove explained, I have illustrated a blank formed to provide two side portions and a cooperating end of the package. It will be obvious that the complete package, including the other end portion, may be provided by employing a pair of formed 35 blanks telescopically associated, in which case each member of the two-part package structure will provide an end portion and contiguously associated sides. In the alternative, both end portions may be provided by a single blank, formed 40 as shown in Fig. 1, with the addition of marginal portions 6, 7 and 8 duplicated along the opposite edge of the blank in the upper part of the figure, and folded and manipulated exactly as described and explained in connection with the 45 lower marginal edges, 6, 7 and 8 shown in the figure.

It is to be understood that the invention has been shown and described in a certain preferred form of embodiment only, merely by way of exemplification. The invention is capable of embodiment in other and further modified forms, and all such modifications, to the extent that they embody the principles of the invention as 50 pointed out in the appended claims are deemed 55 to be within the scope and purview thereof.

Having thus described my present invention

what I claim and desire to secure by Letters Patent is:

1. A package comprising a sheet folded to provide two integral sides, one side being relatively narrow, and the other side being relatively wide and substantially convexly curved, a portion of the sheet integral with the sides being folded from the sides to provide an end of the package, said end having one of its side boundary lines substantially convexly curved. 80

2. A package comprising a sheet folded to provide two integral sides, one side being relatively narrow, and the other side being relatively wide and substantially convexly curved, the end marginal portions of both sides being folded on themselves and secured together to provide an end of the package. 85

3. A package comprising a sheet folded to provide two integral sides, one side being relatively narrow and substantially concavely curved, and the other side being relatively wide and substantially convexly curved, the end marginal portions of both sides being folded on themselves and secured together to provide a closed end of the package. 90

4. A package comprising a sheet folded to provide side portions, one side being substantially concavely curved and the other side being substantially convexly curved, in combination with integral end marginal portions of the sides folded on themselves and secured together to provide a closed end of the package, the marginal portion of the concavely curved side being transversely slit and opened. 95

5. A package comprising a sheet folded to provide side portions, one side being substantially concavely curved and the other side being substantially convexly curved, in combination with integral end marginal portions of the sides folded on themselves and secured together to provide a closed end of the package, the marginal portion of the concavely curved side being transversely slit and opened in substantial alignment with the median line of said side and secured in opened condition to fix the concave curvature 100 of the side. 105

6. A package comprising a sheet having a body folded to provide side portions of the package and end marginal portions integral with the body, folded on themselves and secured together to 110 provide an end of the package, the end marginal portion of one side being centrally slit and opened whereby said side is substantially concavely curved. 115
